UNITED STATES PATENT OFFICE.

THEODORE GRAETHER OF DETROIT, MICHIGAN, ASSIGNOR TO THE DETROIT STEEL AND SPRING WORKS.

SPRING-MAKING MACHINE.

SPECIFICATION forming part of Letters Patent No. 351,975, dated November 2, 1886.

Application filed July 29, 1886. Serial No. 209,438. (No model.)

To all whom it may concern:

Be it known that I, THEODORE GRAETHER, of Detroit, in the county of Wayne and State of Michigan, having invented new and useful

5 Improvements in Spring-Machines; and I do hereby declare that the following is a full, clear, and exact description thereof, reference being had to the accompanying drawings, which form a part of this specification.

10 This invention relates to new and useful improvements in machines for forming springs; and the invention consists in the peculiar construction, arrangement, and combination into an operative machine of a number of formers, 15 by means of which a blank may be bent into elliptical shape and provided with the usual eyes in the ends at one heating of the blank, all as hereinafter described.

In the drawings which accompany this 20 specification, Figure 1 is a plan of my machine. Fig. 2 is a vertical cross-section on the line x in Fig. 1. Fig. 3 is a vertical section on line y in Fig. 1. Fig. 4 is a plan showing the position of some of the dies in operation. Fig. 25 5 is a perspective view of the blank.

A solid bed-plate or table, A, is supported upon a suitable frame, and near the rear end of this table is journaled in suitable bearings the shaft B, to which the drive-pulley C is attached by 30 means of a clutch, D, of known construction. E is a trip-lever arranged to trip the clutch by acting on the spring-dog F of the clutch and hold it normally open, except when withdrawn from contact therewith by means of the foot 35 lever G.

Upon the shaft B are secured two like cams, H, which bear against the anti-friction rollers a , secured on the back of the movable former I. The latter reciprocates between parallel 40 guides b , and has springs c , which by their tension effect the rearward movement of the jaw. A stationary former, J, is secured to the bed-plate in front of the movable former, and at such distance therefrom that the forward 45 movement of the movable former will bring the opposite curved faces d of the two in such close proximity to each other that a heated steel blank placed between the formers will be bent into the required shape. The movable former I is preferably formed in two parts 50 detachably secured together in any suitable

manner. The two front corners of the former I are cut away at e , as shown, and for the purpose hereinafter explained. A stud, G, projects from the center of the face of the former J, and registers with a corresponding hole, G' , in the face of the movable former I, and when the heated blank is placed between the two formers I J the hole h in the center of the blank is engaged with the stud G, and to permit the operation to be performed with the tongs by means of which the heated blank has to be handled, I form a suitable recess, i , at the base of said stud.

Near the front corners of the table are secured in vertical guides K the two vertically movable formers L, which operate in connection with the apertured steel blocks M, all so arranged that, if a heated blank is placed flat on the table and projecting with its free ends under the formers L, the latter in descending will bend down the ends of the blank, as shown in Fig. 3. To hold the blank in proper position for this operation, the table is provided with a central stud, k , with which the hole h in the blank is engaged, and two guide-studs, l , prevent any other accidental displacement. A recess, m , in the front edge of the table, near the stud k , permits of handling the heated blank in this position with the tongs.

The formers L are actuated by means of levers N and cams O, and set-screws n in the rear ends of the levers N permit of regulating the throw of said levers to obtain the proper movement of the formers L.

P P are two formers horizontally movable in suitable guides, Q, on top of the table. They operate, as shown in Fig. 4, in connection with the cut-away corner e of the former I, to complete the eyes on the ends of the blanks after they have been partially formed by the formers L. To this end the forward end of each former is provided with the rounding recess o and the cheeks p q , the former of which projects beyond the latter. By these means the cheek p travels in advance and protects that portion of the eye already formed by the previous operation. The corners of the formers J are also preferably cut away, as at f , to fit the cheek p , as shown. Each of the formers P is actuated by means of a lever, R, which operates in connection with a cam, S,

on the shaft B, and for the purpose of adjustment the pivots *r* of the levers R are adjustably secured to the bed plate in any suitable manner.

5. The levers R and N, hereinbefore mentioned, have suitable springs to retract them.

In practice a steel blank provided, as shown in Fig. 5, with the central hole, *h*, is properly heated and placed with the aid of tongs on the front end of the table, as shown in dotted lines in Fig. 1, the hole *h* engaging with the stud *k*, and the ends of the spring projecting under the formers L. This accomplished, the workman releases the trip-lever E from engagement 15 with the clutch D by actuating the foot-lever, when the succeeding revolution of the shaft B causes the formers L to descend and form the initial bend of the eyes, as shown in Fig. 3. The motion of the shaft B having been arrested by the automatic action of the trip-lever after one revolution, the workman proceeds to remove the blank and place it for the next operation edgewise on the table between the two formers I J, with the hole *h* engaging 25 on the stud G of the former J, as shown in Fig. 1. The workman then again starts the machine for another revolution, when the former I, in approaching the former J, bends the spring into shape, and then keeps it firmly clamped 30 between. During this clamping action, (which, owing to the shape of the cams H, lasts for a part of the revolution of the shaft B,) the formers P start up and complete the eyes of the spring. The two successive operations to 35 which the blank has thus been subjected can be carried out with one heat of the blank, and the advantage of my machine in this respect is self-evident.

What I claim as my invention is—

40 1. In a spring bending and forming machine, the following elements combined: a table, a pair of movable formers operating in connection with apertures in the table to form the initial bend of the eyes, a movable and a 45 stationary former arranged to bend the spring,

and a pair of movable formers operating in connection with the bending-formers to complete the eyes, all arranged and operating substantially as described.

2. In a spring bending and forming machine, 50 the combination of the table A, the stationary former J, having the stud G and recess *i*, and the movable former I, all arranged to operate substantially as described.

3. In a spring bending and forming machine, 55 the combination of the formers I J, arranged to clamp the spring, and having the cut-away corners *e f*, and the movable formers P, having the rounding recess *o*, and the cheeks *q p*, all arranged to operate substantially as described.

4. In a spring bending and forming machine, 60 the combination of the table A, having the apertures M, and the movable formers L, all arranged to operate substantially as described.

5. In a spring bending and forming machine, 65 the combination of the table A, having the studs *k l* and recess *m*, the vertically-movable formers L and the apertures M in the table, all arranged to operate substantially as described.

6. In a spring bending and forming machine, 70 the combination, with the formers P, I, and J, of the shaft B, cams S, levers R operated thereby, and cams H, said cams being partly eccentric and partly concentric, substantially as described.

7. In a spring bending and forming machine having the movable formers L, P, and I, substantially as described, the combination of the shaft B, having actuating connections with said formers, the clutch D on said shaft, and the self-acting trip-lever E, substantially as and for the purposes described.

THEODORE GRAETHER.
